UNITED STATES PATENT OFFICE

MOSES F. CARR, OF LEXINGTON, MASSACHUSETTS, ASSIGNOR TO UNITED-CARR FASTENER CORPORATION, OF CAMBRIDGE, MASSACHUSETTS, A CORPORATION OF MASSACHUSETTS

SNAP FASTENER

Application filed January 18, 1930. Serial No. 421,756.

My invention aims to provide improvements in separable fastener members.

In the drawings which illustrate preferred embodiments of my invention:—

5 Figure 1 is a part section and part elevation of a resilient stud installation showing the stud secured to the carrying medium by means of a tack;

10 Fig. 2 includes a plan and a side elevation of the stud member shown in Fig. 1;

Fig. 3 is a section similar to the one illustrated by Fig. 1, except that the rolled edge of the base of the stud member is omitted;

15 Figs. 4 and 5 are sections taken through modified forms of studs showing the folded over portion of the base located at the top side of the base instead of at the bottom side, as shown in Figs. 1 and 2, and showing the yieldable portions formed integral with the 20 folded over portion; and

Fig. 6 includes a plan and side elevation of the stud member shown in Fig. 4.

Throughout the drawings like numerals will be used to indicate like parts.

25 Referring to the embodiment of my invention illustrated in Figs. 1 and 2, I have shown a snap fastener stud (Fig. 1) secured to a flexible carrying medium 1 by means of a tack 2.

30 The same general ideas may be followed in connection with a socket instead of a stud in all the embodiments of invention illustrated, the changes being in the formation of the annular walls, as will be apparent to anyone skilled in the art.

The stud member (Figs. 1 and 2) which I have selected for illustrative purposes is pressed from a single sheet of metal and has a base portion 3 from which is pressed an upwardly projecting annular wall flared outwardly to provide a neck 4 and a head 5.

40 The center of the head is pressed downwardly to provide a cup-shaped portion 6 surrounded by the annular wall which provides the neck and head of the stud, as best illustrated in Fig. 1. The bottom 7 of the cup-shaped portion 6 is pressed out to provide an aperture 8 above which is provided a dome 9 for receiving and clenching the shank of the tack 2 or other attaching element.

The wall 10 of the cup-shaped portion 6 and the wall which provides the neck and head of the stud are divided by a number of slits 11 which have their ends terminating in the bottom 7 of the cup-shaped portion and in the base 3 of the stud, as illustrated in Figs. 1 and 2. These slits permit contraction and expansion of the head 5 for engagement with and disengagement from a cooperating socket.

45 Stud members of the type above-described may be secured to the carrying medium 1 by means of a tack 2 or other element of well-known construction in the manner illustrated in Fig. 1. During attachment, the shank 12 of the attaching element is forced through the carrying medium 1 and is guided through the aperture 8 by the wall portion 9 into the cup-shaped portion 6 where the protruding end is upset and clenched by the generally curved dome 9.

50 The dome 9 is of importance because it conceals the upset portion of the shank of the attaching element and affords a neat appearance to the fastener.

55 At the periphery of the base 3 I have provided a flange 13 which is located beneath and in spaced relation to the base. This flange has two useful purposes. First, it exerts a pressure on the carrying medium 1 and grips a portion of it tightly between the flange and the cap or head of the tack 2, as clearly shown in Fig. 1. Second, it spaces the base 3 from the carrying medium 1 thereby leaving those portions of the base, between the slits 11, free to yield toward the carrying medium without interference when the head of the stud is contracted.

60 In Fig. 3 I have illustrated an installation which is substantially the same as in Fig. 1. In this instance, however, I have eliminated the flange 13 beneath the base to show that it is not absolutely essential to space the base 3 from the carrying medium, although it is desirable.

65 Referring now to the embodiment of my invention illustrated in Figs. 4 through 6, I have shown a fastener stud installation which includes a stud part for substantially the same use as that shown in Figs. 1 and 2.

but constructed in a substantially different manner. Instead of bending the flange 13 under the base 3 I have bent it inwardly over the base so that that base may present a 5 smooth continuous surface perforated only by the tack-receiving aperture 8. Thus the base 3 may be in contact with the carrying medium 1 throughout its entire surface, as shown in Figs. 4 and 5.

10 The two walls which provide the socket-engaging portion of the stud are formed as a continuation of the flange or connecting portion 13. However, the wall 10 terminates in a free edge spaced from the base 3 15 and yields with the wall which provides the head and neck. By arranging the walls as shown in Fig. 4 there is provided a more readily yieldable head which is less apt to become set because there is no resistance set 20 up by the wall 10. Furthermore, the flange or connecting portion 13 is spaced from the base so that the slits 11 may divide the flange or connecting portion 13 and provide longer yieldable portions which are not interferred 25 with by the base 3.

In Fig. 5 I have shown the same type of fastener as that illustrated in Figs. 4 and 6, but with the flange or connecting portion 13 and base 3 in contact. This fastener is a 30 commercially operable one, but the yielding portions are more stiff and have a greater tendency to become set than is the case with the stud shown in Fig. 4.

While I have illustrated and described 35 preferred embodiments of my invention, I do not wish to be limited thereby, because the scope of my invention is best defined by the following claims.

I claim:

40 1. A snap fastener member formed entirely from a single piece of metal and comprising a base portion, a pair of annularly arranged connected walls extending at substantially right angles with relation to said base 45 portion and at least one of which is secured thereto, means permitting yielding movement of said walls when engaged with and disengaged from a cooperating snap fastener member, means provided by one of said walls 50 for maintaining engagement with a cooperating fastener member and a dome-shaped attaching portion formed as a part of said fastener member and surrounded by said walls and open at one side only to receive 55 an attaching element to be upset within said dome-shaped portion, said dome-shaped attaching portion presenting a curved surface toward said opening.

60 2. A snap fastener member comprising a base portion perforated only by a relatively small aperture to permit passage of the shank of an attaching element, a pair of connected annularly arranged walls extending at substantially right angles with relation to said 65 base portion and one of which is secured

thereto, the other of said walls having a free edge terminating between the outer edge of said walls and the said base portion, means permitting yielding movement of said walls when engaged with and disengaged from a 70 cooperating snap fastener member, means provided by one of said walls for maintaining engagement with a cooperating fastener member and a dome-shaped attaching portion formed from said base and surrounded by said walls and open at one side only to receive an attaching element to be upset within 75 said dome-shaped portion.

3. A snap fastener stud member having a base portion, a wall extending from said base portion and flared outwardly to provide a head and a neck, a second wall connected to and encircled by said first mentioned wall and having a free edge terminating in spaced relation to the base portion, said walls being divided by slits to permit contraction and expansion of the stud head, and a dome-shaped portion formed from said base and encircled by both walls and providing means 80 for receiving and clenching an attaching element.

4. A snap fastener member comprising a base portion, a pair of annularly arranged connected walls extending at substantially right angles with relation to said base portion, means permitting yielding movement of said walls when engaged with and disengaged from a cooperating snap fastener member, means provided by one of said walls 85 for maintaining engagement with a cooperating fastener member and a dome-shaped attaching portion formed as a part of said fastener member and surrounded by said walls and open at one side only to receive an attaching element to be upset within said dome-shaped portion and a connecting portion extending inwardly from the periphery of said base to the lower edge of one of said walls thereby connecting said wall to said base to form a single unit.

5. A snap fastener stud member having a base portion, a wall extending from said base portion and flared outwardly to provide a head and a neck, a second wall connected to and encircled by said first mentioned wall and having a free edge terminating adjacent to said base portion and a dome-shaped portion formed from said base and encircled by both walls and providing means for receiving and clenching an attaching element.

In testimony whereof, I have signed my name to this specification.

MOSES F. CARR.
